US0D1070858S

(12) **United States Design Patent** (10) **Patent No.:** **US D1,070,858 S**
Tong (45) **Date of Patent:** **** Apr. 15, 2025**

(54) **KEYBOARD**

(71) Applicant: **RAZER (ASIA-PACIFIC) PTE. LTD.**,
 Singapore (SG)

(72) Inventor: **Ien Yu Tong**, Singapore (SG)

(73) Assignee: **Razer (Asia-Pacific) Pte. Ltd.**,
 Singapore (SG)

(**) Term: **15 Years**

(21) Appl. No.: **29/749,075**

(22) Filed: **Sep. 2, 2020**

(51) LOC (15) Cl. **14-02**

(52) U.S. Cl.

USPC **D14/392**

(57) **CLAIM**

The ornamental design for a keyboard as shown and described.

DESCRIPTION

FIG. 1 is a perspective view of a first embodiment of a keyboard, showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a rear elevational view thereof; and

FIG. 7 is a front elevational view thereof.

FIG. 8 is a perspective view of a second embodiment of the keyboard;

FIG. 9 is top plan view thereof;

FIG. 10 is a bottom plan view thereof;

FIG. 11 is a left side elevational view thereof;

FIG. 12 is a right side elevational view thereof;

FIG. 13 is a rear elevational view thereof; and,

FIG. 14 is a front elevational view thereof.

The broken lines are for illustrating portions of the keyboard which form no part of the claimed design.
